United States Patent Office.

DAVID SAUNDERS, OF BROOKLYN, NEW YORK.

Letters Patent No. 65,124, dated May 28, 1867.

IMPROVEMENT IN PIPE-VISES.

The Schedule referred to in these Letters Patent and making part of the same.

TO ALL WHOM IT MAY CONCERN:

Be it known that I, DAVID SAUNDERS, of Brooklyn, in the county of Kings, and State of New York, have invented certain new and useful improvements in Pipe-Vises, by which I mean vises adapted to hold pipes or other round objects of different sizes; and I do hereby declare that the following is a full and exact description thereof.

My improved vise will hold pipes of different sizes, and will let them in and out readily by a lateral movement instead of an end movement, and allows the pipe to be held either upright or at any inclination required. The ability to hold pipes at different angles is important, because in cutting threads on the ends, or otherwise treating pipes, it is desirable to hold them as nearly upright as may be, and while short pieces may be held, under ordinary circumstances, directly upright, longer pieces require to be inclined to an extent depending on the length, as will be obvious. The introduction and removal of the pipes by a lateral movement, allow the pipes to be removed from my vise after a T-piece, an elbow, or other fixture has been attached at each end. There have been many pipe-vises before known which possessed these qualities singly, but I know of none which possess them altogether. I employ a peculiarly constructed sliding-jaw as one portion of my vise, which is secured upon the operating screw in a manner which will be readily understood, and which affords increased strength and firmness to this important connection.

I will proceed to describe what I consider the best means of carrying out my invention. The accompanying drawings form a part of this specification.

Figure 1 is a section, on the line S S in fig. 2.

Figure 2 is a plan view of my vise, showing a pipe held within the jaws.

Similar letters of reference indicate like parts in all the figures. Tints are employed only to aid in distinguishing parts, and do not indicate material. The material of the whole may be iron and steel.

A A¹ is a casting adapted to be firmly secured upon the bench by screws introduced through the holes a. A¹ is an upright flange, to the front face of which is applied a corresponding flange, B¹, of the casting, which contains and supports the effective portions of my vise. This casting entire I will designate generally as B. One of its most important characteristics is the ample opening, H, provided in one side adjacent to the jaws, which seize and hold the pipe, and which is of sufficient size to allow the largest pipes or other analogous articles to be introduced and removed freely by a simple lateral movement. The entire casting B and its connections turn in various positions, as required. The parts A¹ and B¹, which I have here termed flanges, are finished in the form of nearly circular disks, and are bolted together by a screw-bolt, C, which passes through the centre of each, by which the force with which the flanges are held together may be graduated at will. When it is desired to change the position of the casting B, the screw C may be slackened, and after B is adjusted the screw C may be tightened again. In many cases it will suffice to allow the screw C to be moderately set up all of the time, so that the casting B may be adjusted by the force of a strong hand without touching the screw. Two pieces of hardened steel having V-shaped dentated recesses, are fitted in the casting B in the position indicated by b¹ b². The space between them is a little greater than the thickness of one of the pieces, and is sufficient to allow the free entrance of a third piece of steel of similar thickness. D¹ D² are respectively the halves of a slide which is traversed in the ways B² B², in the interior of the casting B, by means of the screw E, which is capped through the part B³, bolted upon the front of B, as represented. The parts of this compound slide D¹ D² are firmly bolted together by the screw-bolts m. This slide carries a piece of hardened steel, d, which is adapted to enter the recess or space before described between the similar pieces b¹ b². The general arrangement of the pieces b¹ b² and d is adapted to take hold of and firmly hold the pipes or other round objects of different diameters, holding them with equal firmness, whether they be one-half inch or two inches in diameter. When the combined slide D¹ D² is driven inward to a great extent, a portion of its steel piece d is received between the steel pieces b¹ b², and when it is drawn back to its fullest extent the steel piece d is entirely clear from the pieces b¹ b², and allows the pipes to be introduced and removed by a side movement, as will be readily understood. It will be observed that the adjusting in the angular position of the entire casting B and its connections, by turning it around upon the piece A, as above suggested, does not in any wise interfere with the relations of the working parts of the vise to each other. The screw E, provided with any approved means for

turning it, is fitted with a strong head or knob, E¹, at its inner end, which is received within a corresponding recess finished in the interiors of the two halves of the compound slide D¹ D². The neck between the head E¹ and body, or threaded portion of the screw E¹, is of smaller diameter, and receives strong and nicely-finished internal lips on the parts D¹ D². The parts being properly turned and bored to correspond with each other, and allow a tight and easy fitting, the halves are applied upon the head E¹ before being bolted together, and the setting up of the screws m confines the parts of the compound slide together with the same rigidity as if the whole were one piece, while the connection with the screw is stronger, and will endure more violent strains than ordinary fittings of this kind.

Having now fully described my invention, what I claim as new therein, and desire to secure by Letters Patent, is as follows:

I claim the improved pipe-vise herein described, turning on the axis C, and having the side opening H, to allow the introduction and removal of the work, the several parts being combined and arranged substantially as and for the purpose herein set forth.

D. SAUNDERS.
